Primary Examiner — Daniel J Domino*Assistant Examiner* — Samina Vieth(57) **CLAIM**

The ornamental design for a monitor, as shown and described.

DESCRIPTION

FIG. 1 is a perspective view of a monitor showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another perspective view thereof.

The dashed broken lines depict portions of the monitor in which the design is embodied that form no part of the claimed design.

1 Claim, 7 Drawing Sheets(56)
